UNITED STATES PATENT OFFICE.

WILLIAM HAINSWORTH, OF PITTSBURG, PENNSYLVANIA.

INGOT-MOLD.

SPECIFICATION forming part of Letters Patent No. 267,880, dated November 21, 1882.

Application filed August 31, 1882. (No model.)

To all whom it may concern:

Be it known that I, WILLIAM HAINSWORTH, a citizen of the United States, residing at Pittsburgh, county of Allegheny, State of Pennsylvania, have invented or discovered a new and useful Improvement in Casting Steel Ingots; and I do hereby declare the following to be a full, clear, concise, and exact description thereof, reference being had to the accompanying 10 drawings, making a part of this specification, in which—like letters indicating like parts—

Figures 1 and 2, Sheet 1, are vertical sectional views of my improved ingot-mold, the sections being taken in the planes of the lines 15 $x x$ and $x' x'$, respectively, of Fig. 3. Fig. 3 is a sectional plan view of the mold, the planes of section being indicated by the broken line $x^2 x^2$, Fig. 1. Fig. 4 is a perspective view of a steel ingot illustrative of the form cast in the 20 mold, Sheet 1; and Fig. 5 illustrates by a perspective view a steel deck-beam reduced by rolling from the ingot, Fig. 4. Figs. 6, 7, and 8, Sheet 2, are views similar to Figs. 1, 2, and 3, respectively, of my improved mold, illustrating 25 certain modifications in construction and showing a form adapted to make an I-beam ingot, the planes of section in the respective figures being indicated by the lines $z z$, $z' z'$, and $z^2 z^2$. Fig. 9 illustrates by a perspective view 30 a steel ingot as made in the mold, Sheet 2; and Fig. 10 is a similar view of an I-beam reduced by rolling from the steel ingot, Fig. 9.

In rolling certain shapes—for example, deck-beams—from steel ingots it is very advantageous and practically necessary that the ingot should be contracted somewhat in thickness along its central part, or, in other words, should have greater width of section at or near two opposite sides than at some one or more intermediate points—for example, as illustrated in Figs. 4 and 9. Like advantages in reduction are also secured for many other shapes, though such conditions may not be essential, as in making I-beams, railroad-rails, angles, channels, &c. Ingot-molds as ordinarily constructed are unsuited for casting steel ingots having the characteristics of form described, from the fact that the form of the mold, especially when expanding by heat, prevents the normal contraction of the ingot in cooling, and the steel, being in a soft and granular condition, is rupt-

ured across the contracted portion of the ingot by the opposing strains incident to the expansion of the mold and the contraction of the ingot. I have illustrated this action in part in Fig. 4, the general direction of forces being illustrated by arrows. The expanding sides of the mold, bearing against the inside faces of the ingot projections $r r$, press outward in the direction of the arrows $y y$, or at least prevent the approach of such parts, while the contracting movement of the ingot in cooling is toward the center, as indicated by the arrows $y' y'$. The sides of the mold thus prevent the normal movement of the metal in the ingot, and rupture necessarily follows, usually across the central or contracted part, r' .

My invention relates to the casting of steel ingots of the general form described, and to the construction of a metal mold by which such casting is made practicable without injury to the ingot, such mold consisting of yielding side pieces for shaping the contracted portion of the ingot, with means for supporting such side pieces, expanding them by heat prior to pouring in the steel, and moving them back to permit unobstructed contraction of the ingot, as hereinafter more fully described and claimed.

On Sheet 1 of the drawings I have illustrated my invention as applied in making steel ingots R, Fig. 4, for deck-beams S, Fig. 5.

The mold, Figs. 1, 2, and 3, is constructed as follows: A rectangular case, A, is employed, open at its ends, and having two opposite sides, $a a'$, of proper form to give the desired shape to the outer faces r^3 and r^4 of the ingot, one such side, a , in the present instance being flat, and the other, a' , being concave or hollowed somewhat to give a rounded face, r^4 , to the ingot. These particular forms are not essential, however, but may be varied at pleasure with reference to the particular article to be produced. This case rests upon a plate, B, and that upon a bed, D, the central part, d , of which is raised and corresponds in form of cross-section to the mold-cavity A', which it enters, and thus forms a bottom chill as well as a bearing or support for the movable sides of the mold-cavity. These movable sides are similar in construction, each consisting of parts $e e' e^2$, (see Fig. 3,) which fit closely to each other and to the ends of the sides $a a'$, forming practically

a continuous wall or inner surface, corresponding in form to the inwardly bent or contracted sides r^5 of the ingot. The form in cross-section of these pieces $e\ e'\ e^2$ is not material, except that sufficient clearance should be provided in rear of them and the back of the joints to permit freedom of movement of one or all from the position shown, Fig. 3, outward toward the sides of the case. At the bottom these pieces rest upon the plate B and against the raised chill d , and at the top they bear by lugs or projections e^4 against a rim, i , which is seated in a rabbet or recess, i' , in the top edge of case A. The movable pieces are held in place against such bearings by a body of sand, C, or other similar earthy matter—as ashes, pulverized coke, &c.—which is packed in the space between the sides of case A and the back face of the pieces; and in order to hold the pieces firmly in place while the sand is introduced, wedges c (see Fig. 6) may be pressed down between them and the case, which will be withdrawn as the sand is packed. Before introducing the sand it is by preference heated quite hot—say to $1,000^{\circ}$ Fahrenheit, more or less. This may be done in any suitable heating stove or furnace, and the hot sand be tapped direct into the spaces to be filled. The pieces $e\ e'\ e^2$ and the sides of the case will become heated by contact with the hot sand to or nearly to the temperature of the latter, and will be expanded thereby. If the sand be heated to a high degree, this expansion of the mold will reach a considerable amount of the full expansion caused by contact with the molten steel of the ingot, since it is a well-known fact that up to, say, $1,000^{\circ}$ Fahrenheit temperature iron expands much more rapidly than at temperatures above that degree. This expansion enlarges the mold in the direction of strain upon the ingot, and being done before the metal is poured in, it will materially lessen the tendency to such strain. In order to pack the joints between the parts $a\ a'\ e\ e'\ e^2$, I make longitudinal grooves n in the abutting faces of the joints, which register and form core-passages; and these passages are filled with lime cores n' , or cores of other powdered or other easily frangible material which will withstand the heat and prevent the sand from sifting through the joints into the mold-cavity.

The mold being thus prepared, the mold-cavity is filled with molten steel in the usual way of doing such work. As the exterior crust hardens and slowly contracts, the sand packing C will yield under the pressure imposed upon the side pieces, $e\ e'\ e^2$, allowing them to move outward and relieve such strain. As soon as the crust of the ingot has cooled sufficiently to "stand," and before any great degree of contraction therein has taken place, the sand packing C is tapped out by suitable openings, b , at the bottom of case A, thus withdrawing back support from the movable side pieces and permitting them to move outward freely under contracting pressure from the cool-

ing ingot, thereby leaving the ingot practically free from any confinement which would in any way impose a strain upon it, to prevent normal contraction and disposition of the molecules of metal of which it is composed. When the ingot is cooled sufficiently the mold is stripped off by raising the base-plate B by lifting-rod B'; also, the case A may be removed separately by lifting on the handles A². The ingot will thus be left standing on the chill d , and may be subsequently handled in the usual way. The ingot R thus formed is especially designed for reduction by rolling into deck-beams S, Fig. 5, and the rounded side r^4 is provided with special reference to the formation of the rounded head s . The side r^3 is reduced to the flanged face s^2 , and the contracted portion r' to the web s' . This reduction may be made by any form of suitable grooved rolls—such, for example, as are used for analogous shapes in iron; and I do not deem it necessary to show the same, as the peculiar difficulties which would be involved in reducing such a product from a rectangular billet or ingot of steel will not be encountered—for example, raising the projections r without seams and markings which could not be removed.

In Figs. 6, 7, and 8, Sheet 2, I have illustrated substantially the same construction of mold, adapted in form to the making of I-beam ingots, and I have lettered corresponding parts of this mold and that of Sheet 1 with the same letters of reference. Instead, however, of employing three movable side pieces, as in Sheet 1, I make use of two, $m\ m$, on each side, which match with core-packed joints n' , and are backed with a yielding body of sand or equivalent material, C, as before described.

The operation of using this mold is the same as above described, and need not be repeated.

I do not wish to limit my invention to any specific number or form of movable or yielding side pieces, as for certain forms of ingots one such movable side wall may be formed in one piece, and thereby relieve the ingot from strain in cooling, which is one important object of my invention. Also, such movable piece or pieces may form one, two, or even all the sides of the mold-cavity, and thereby one or more concave or hollowing sides may be made lengthwise on the ingot, and corner or other elevations be made on such sides, which will assist materially the subsequent reduction of such ingot to the desired form of product, whether deck-beams, I-beams, railroad-rails, angles, channels, or other forms and shapes.

So far as I aware, it is new with me to cast in metal molds steel ingots with one or more concave sides, as described and shown, and such ingots are designed to become an important article of manufacture, sale, and use in the arts. Such an ingot is not claimed herein, however, but will form the subject-matter of a separate application for patent.

I claim herein as my invention—
1. An ingot-mold having an inclosed space or

chamber separated from the mold-cavity by a movable metallic wall with one or more tap-holes at its lower end, in combination with a body of heated sand or other equivalent heated 5 and yielding packing in such chamber or space, substantially as described, whereby the metallic wall is held in place by a yielding support and heated and expanded by contact therewith.

10 2. The combination of mold-case A, one or more separate side pieces, forming movable side walls of the mold-cavity, and a body of heated sand or equivalent heated and elastic packing between such movable walls and the 15 sides of the case, substantially as set forth.

3. An ingot-mold having in combination an outer case and separate inclosed pieces, forming one or more inwardly projecting or curved sides of the mold-cavity, such pieces being 20 movable transversely within the case, and a body of sand or equivalent yielding support between the sides of the case and such pieces, substantially as described, whereby the movable pieces are held in place to form convex 25 or inwardly-bent sides of the cavity as against the weight of metal in the ingot, but may yield backward and enlarge the cavity under contracting pressure of the ingot.

4. The combination of an outer mold-case, 30 forming two opposite sides of a mold-cavity, separate inclosed side pieces in any desired number, forming one or more convex or inwardly-projecting sides of the cavity, such pieces being movable transversely within the case, and a body of sand or equivalent packing 35 between the backs of such pieces and the sides of the case, substantially as and for the purposes set forth.

5. In combination with an outer mold-case,

separate inclosed side pieces in any desired 40 number, forming one or more of the side walls of the mold-cavity, such pieces being movable transversely within the case, a yielding body of sand or equivalent packing between the backs of such pieces and the case, and one or more tap-holes at the bottom of the case for drawing off 45 such sand or earth, substantially as set forth.

6. The combination of an outer mold-case, 50 separate inclosed side pieces in any desired number, forming one or more of the side walls of the mold-cavity, such pieces being movable transversely within the case, a yielding body of sand or equivalent packing between such pieces and the case, and frangible cores in the joints made by the movable pieces, substantially 55 as set forth.

7. The combination of base D, having raised chill d thereon, bed-plate B, case A, side pieces, $e e' e^2$, in any desired form and number, rim i , and sand back C, substantially as set forth. 60

8. The mold-case A, having one or more tap-holes, b , at its lower edge, in combination with base-plate B, movable pieces $e e' e^2$, in any desired form and number, forming one or more sides of the mold-cavity, rim i , and sand body 65 C, substantially as set forth.

9. The combination of case A, sand body C, movable pieces $e e' e^2$, in any desired form and number, forming one or more sides of the mold-cavity, and frangible cores n' in the joints made 70 by such pieces, substantially as set forth.

In testimony whereof I have hereunto set my hand.

WILLIAM HAINSWORTH.
